UNITED STATES PATENT OFFICE.

FREDERICK A. ARBENZ, OF WEST HOBOKEN, NEW JERSEY.

DESIGN FOR FABRIC.

SPECIFICATION forming part of Design No. 36,218, dated February 3, 1903.

Application filed July 26, 1902. Serial No. 117,216. Term of patent 14 years.

To all whom it may concern:

Be it known that I, FREDERICK A. ARBENZ, of West Hoboken, county of Hudson, and State of New Jersey, have invented and produced 5 a new, original, and ornamental Design for Fabrics, of which the following is a full, clear, and exact description, reference being had to the accompanying drawing, representing the design upon a piece of dress goods.

10 The drawing shows a piece of fabric containing the entire design. The lines *a b* and *c d* divide the design into three fields; but in each field the ornamental design consists of

figures, (rosettes,) as shown in the drawing, which are arranged in rows and gradually increasing and decreasing in size. This design is repeated throughout the entire length of the piece of such fabric as it is produced in the loom or is printed thereon. 15

I claim as my invention—

The ornamental design for a fabric as herein shown and described.

FREDERICK A. ARBENZ.
